UNITED STATES PATENT OFFICE

THOMAS T. WYNN, OF NEW YORK, N. Y.

DESIGN FOR A HAND FOR A TIMEPIECE OR SIMILAR ARTICLE

Application filed February 12, 1930. Serial No. 34,510. Term of patent 7 years.

To all whom it may concern:

Be it known that I, THOMAS T. WYNN, a citizen of the United States, residing in the city, county, and State of New York, have invented a new, original and ornamental Design for a Hand for a Timepiece or Similar Article, of which the following is the specification, reference being had to the accompanying drawing, forming part thereof.

The figure is a plan view of a hand for a time-piece or similar article showing my new design.

I claim:

The ornamental design for a hand for a timepiece, or similar article, substantially as shown.

Signed in New York, in the county and State of New York, this eighth day of February, 1930.

THOMAS T. WYNN.
